Primary Examiner — Janice Hallmark(74) *Attorney, Agent, or Firm* — Barnes and Thornburg LLP(57) **CLAIM**

The ornamental design for a vent hood, as shown and described.

DESCRIPTION

FIG. 1 is a perspective view of a vent hood showing our new design;

FIG. 2 is a front view thereof;

FIG. 3 is a back view thereof;

FIG. 4 is a side view, the opposite side is a mirror image, thereof;

FIG. 5 is a top view thereof; and,

FIG. 6 is a bottom view thereof.

The broken lines depict environmental subject matter only and form no part of the claimed design.
